CONTAINER WITH INSERT

John W. Meinhardt, Dallas, Tex., assignor to Gay-Lord Container Corporation, St. Louis, Mo., a corporation of Maryland

Application July 8, 1952, Serial No. 297,655

6 Claims. (Cl. 229—15)

1

This invention appertains to a container with insert, and more particularly to a novel insert for dividing a container into two or more compartments and reinforcing the container walls. The insert may be made of solid fibreboard, corrugated fibreboard or any other suitable material.

It is often necessary in the transportation of easily damaged articles such as bakery goods and the like, to protect the articles against injury without requiring the use of expensive individual packaging. For instance in the delivery of bread, it is highly desirable to provide a large, sturdy, re-usable container which will effectively protect the bread from all injury or contact. Furthermore, it is important from a material saving standpoint that the container should have provision for receiving at least two layers of loaves of bread. To provide maximum protection, it is necessary that each layer of loaves be supported completely independently of the adjacent layer. As cartons of bread and similar items are often stacked in delivery vans, it is also important that each container be of a construction which will afford adequate support for any load stacked above, without injury to its own contents. Also, since often the delivery man takes out single rows of loaves, it is highly desirable that the container be rigidly self-supporting without any dependency whatsoever on its contents. It is therefore an object of this invention to provide a dividing insert for supporting contents within a container, which has side wall reinforcing portions which strengthen the adjacent walls of the container as well as provide added stacking support for top loads.

It is an object of this invention to provide a unitary dividing insert of sufficient strength to independently support the weight of at least one-half the contents of the container.

Another object of this invention is to provide an insert having a two-ply dividing member which laterally reinforces and stiffens the body of the container.

A still further object is to provide a dividing and reinforcing insert which is automatically collapsible within the container as the container is flattened for shipment or storage, and which is automatically erectable when the container is opened to the loading position.

Another object is to provide a container dividing and reinforcing insert wherein the resiliency of the material and the resulting natural tendency of the components of the insert to unfold, permits the insert to be positioned within a snug-

2

ly fitting container body without manipulation or requiring the use of any fastening means whatsoever.

A still further object of this invention is to provide a dividing insert for a container wherein the dividing panels have no exposed raw or cut edges which might injure the contents during the loading of the container.

Other objects and advantages of this invention will be apparent to those skilled in the art upon a full and complete understanding of the construction and operation of this device.

The invention also consists in the parts and arrangements and combinations of parts herein-after described and claimed. The accompanying drawings form a part of this specification and like numerals and symbols therein appearing refer to like parts wherever they occur.

Fig. 1 is a plan view of a blank having a dividing and reinforcing insert employing a preferred form of this invention.

Fig. 2 is a perspective view of a dividing and reinforcing insert employing a preferred form of this invention shown in position inside a container which is shown in dotted lines.

An insert A, which is shown in a preferred form in Fig. 1, is provided with a dividing partition and article supporting panel 10 which is defined on its end margins by transverse scores

11. The transverse scores 11 also define the inner margins of end extensions 12 which provide another panel. A parallel pair of longitudinal scores 13 defines the side margins of the dividing panel 10 and the end panel extensions 12.

The longitudinal scores 13 also define the inner margins of flaps 14 and end extension flaps 15. Slots 16 define end edges of the flaps 14, and the end extension flaps 15. In the illustrated embodiment of the insert A, the dividing partition and article supporting panel 10 is dimensioned so

as to make its length equal to the interior length of the container into which it is to be inserted. Similarly, its width is substantially equal to the interior width of the container.

The end extensions 12 are preferably dimensioned so that the sum of their lengths is equal to the length of the dividing panel 10 thereby providing a continuous two-ply dividing panel structure. Also in the preferred form of the invention as shown in Fig. 1, it is desired that the dividing panels be spaced between the panel flaps 14 and the end extension flaps 15 to a position equidistant and substantially parallel to the container side

50
45
55

wall. The side flanges 14 and 15 thereon are of a uniform width equal to substantially one-half the distance between the side walls of the container. However, it is obvious that the dividing partition, article supporting and reinforcing insert of this invention is readily adapted for use in containers of other than rectangular shape. For instance, in a trapezoidal shaped container, the flaps 14 and the end extension flaps 15 could be varied in dimension to properly fit within the modified container. It is also possible that the dividing structure might be disposed within a rectangular container to provide a reinforcing and dividing insert in which the two-ply dividing portion was angularly disposed to the side walls of the container rather than disposed parallel as in the preferred embodiment described or possibly it might be desirable to position the dividing portion nearer one wall than another. In these instances, the dimensions of the flaps 14 and the end extension flaps 15 could be varied so as to orient the dividing portion of the insert as desired.

The dividing partition, article supporting and reinforcing insert shown in Figs. 1 and 2 may be erected in any suitable manner. However, a preferred method is to fold the end extensions 12 about the transverse scores 11 into flatwise relation with the surface of the dividing panel 10. The flaps 14 and the end extension flaps 15 are then folded outwardly about the longitudinal scores 13 into a position at substantially right angles to the previously positioned dividing panel 10 and the flaps 14. Tape 17 may be applied as shown in Fig. 2 so as to maintain the 25 dividing and reinforcing insert A in the erected position. The tape 17 should substantially cover and overlap the joint formed by the juncture of the abutting end extensions 12 and the end extension flaps 15. If desired the dividing panel 10 and end extensions 12 may be stitched, glued or otherwise secured together. However, it is apparent that the tape 17 may be omitted if the 30 reinforcing insert A is positioned within the container since the board tends to constantly force the components into proper position within the 45 container.

The flaps 14 and the end extension flaps 15 are of sufficient strength to independently support the contents carried on the dividing panel 10 and end extensions 12 without the support of the container body section B. Thus in the preferred form, it is apparent that the dividing and reinforcing insert will firmly support the weight of at least one-half the contents of the carrier. This 50 feature is especially desirable when one-half of the contents of the container are removed. The remaining portion of the contents is thereby firmly and securely maintained in position independently of the empty compartment. If desired, the insert A may be glued or otherwise secured to the container B.

The container B consists of a top wall 17, a bottom wall 18 and oppositely disposed upstanding side walls 19 and 20. The container may be closed at the opposite ends E and E' by pairs of oppositely disposed and preferably similarly formed closure flaps 21 which may be integral with the side walls 19 and 20 and other flaps 22 which are preferably similarly formed and which said flaps may be integral with the top wall 17 and bottom wall 18. These flaps 21 and 22, which are preferably at both ends E and E' of the container, serve to maintain the same in erected po-

10 sition when closed. Obviously other types of closures may be utilized.

Further, the container B has fold lines constituting hinge means at its four corners C, C1, C2 and C3.

It will be noted that at the juncture J, where the respective flaps 14 and 15 at opposite sides of the two plies of the partition are folded, the adjacent edges at the folds of these flaps are in substantial abutting relationship.

The scores or fold lines 13 in the insert and the fold lines constituting hinge means at C, C1, C2 and C3 at the corners of the container B provide for automatic erection of the container and the insert therein as shown in Fig. 2 and, likewise, an automatic collapsing along the score and fold lines to a substantially flat condition with the insert, of course, within the container. The erection and collapsing of the container does not require any manual manipulation of the insert whatever and simply by maintaining one of the walls stationary and simultaneously swinging the remaining walls about the score and fold lines of the insert and container respectively, these walls and the two-ply partition and the respective flaps thereon are collapsed to a position in substantial parallel relation to each other.

It is to be understood that the embodiments described herein are illustrative and not restrictive and it is also to be understood that the invention is susceptible to be embodied in other similar or equivalent forms coming equally within the scope of the claims next appearing.

What I claim is:

1. A paperboard container having two upstanding side walls, horizontal top and bottom walls connecting the side walls, one end of the container having a vertical wall constituting openable closure means thereat, and a paperboard container reinforcing and partitioning insert therein, the insert having an article supporting partition member consisting of upper and lower unscored panels of substantially rigid material horizontally disposed within the container and each substantially coextensive with and in parallel spaced relation to the top and bottom walls and thus forming upper and lower article storing compartments within the container, the compartments being accessible from the opened end of the container for inserting articles on or removing same from the upper compartment on the partition member and the lower compartment, a partition supporting and side wall reinforcing flap extending downwardly from each of the opposite side edges of the lower panel of the partition member, a side wall reinforcing flap extending upwardly from each of the opposite side edges of the upper panel of the partition member, said flaps being fixed against their adjacent side walls and the free end edges of the said flaps terminating adjacent the upper and lower inside corners of the container.

2. The container with the insert as defined in and by claim 1, wherein said panels are portions of a folded one-piece blank.

3. The container with the insert as defined in and by claim 1, wherein said partition member comprises a single one-piece blank having folded over end portions constituting one of said panels.

4. The container with the insert as defined in and by claim 1, wherein the said flaps are adhesively fixed to their adjacent side walls.

5. The container with the insert as defined in and by claim 1, wherein portions of the upwardly

5

and downwardly extending flaps at their junctions with the upper and lower panels respectively are in substantial abutting relationship.

6. The container with the insert as defined in and by claim 5, wherein the said flaps are adhesively fixed to their adjacent side walls.

JOHN W. MEINHARDT.
